UNITED STATES PATENT OFFICE.

MICHEAL F. CUBIAC, OF DETROIT, MICHIGAN, ASSIGNEE OF ONE-HALF TO JOHN H. GOSS, OF DETROIT, MICHIGAN.

ADJUSTABLE SCALE-HOLDER.

1,163,512.

Specification of Letters Patent.

Patented Dec. 7, 1915.

Application filed January 6, 1915. Serial No. 843.

To all whom it may concern:

Be it known that I, MICHEAL F. CUBIAC, a citizen of the United States, residing at Detroit, in the county of Wayne and State of Michigan, have invented certain new and useful Improvements in Adjustable Scale-Holders; and I do hereby declare the following to be a full, clear, and exact description of the invention, such as will enable others skilled in the art to which it appertains to make and use the same.

This invention relates to an adjustable scale or rule holder and the primary object of the invention is to provide a device of this nature, which will facilitate the laying out of work by a machinist, pattern maker, or like workman.

Another object of this invention is to provide an adjustable holder for scales, which has a supporting base, having one face thereof perfectly flat for abutment against the working surface of a block of material being worked upon, and to support by this base a rule or scale, for facilitating measuring from the center line of the work.

With the foregoing and other objects in view this invention consists in such novel features of construction, combination and arrangement of parts as will be hereinafter more fully described, illustrated in the accompanying drawing and claimed.

In describing the invention in detail reference will be had to the accompanying drawing wherein like characters designate like or corresponding parts throughout the several views, and in which:

Figure 1 is a side elevation of the improved adjustable scale holder, Fig. 2 is a cross sectional view on the line 2—2 of Fig. 1, Fig. 3 is a cross sectional view on the line 3—3 of Fig. 1, Fig. 4 is a fragmentary view partially in side elevation and partly in section of the scale holding jaw, and Fig. 5 is a detail edge view of a part of the scale holder.

Referring more particularly to the drawing, 1 designates the supporting base of the adjustable scale holder, which is substantially circular in plan and has an annular flange 2 formed upon its lower end. The bottom face 3 of the base support 1 is machined perfectly flat for abutting engagement with a finished working surface of a block of material from which any desired article is to be formed, such as a machine

part, a pattern or a machine tool, depending upon the use to which the adjustable scale holder is put.

The supporting base 1 has secured thereto and projecting upwardly therefrom vertical standards 4 and 5, which are circular in cross section and have their lower ends seated in openings formed in and extending vertically through the supporting base 1. The standards 4 and 5 are placed side by side, and are positioned equidistant of and upon opposite sides of the central axis of the supporting base 1. The standards 4 and 5 have sleeves 6 and 7 mounted thereupon respectively, which sleeves are joined by the web 8. The sleeve 7 is split and has tangentially extending ears 9 formed thereupon which are perforated for receiving the shank 10 of a thumb screw 11. The ear 9 is provided with a smooth perforation, while the perforation which extends through the ear 9 is internally screw threaded, for clamping the sleeve 7 firmly upon the standard 5, and holding the sleeves 6 and 7 and the web 8 which connects them at different adjusted vertical positions upon the standards 4 and 5.

The sleeve 6 has an extension 12 formed thereon, which extension is provided with a facial recess 13. The extension 12 is also provided with the internally screw threaded bore 14 extending therein from its outer end, which bore receives the shank of a thumb screw 15, the head of which is adapted for engagement with one side or edge of a scale or rule 16 for clamping the scale against the inner wall of the socket or recess 13 and between the inner surface of the head of the thumb screw 15 and the shoulder 17 formed at the inner terminal of the recess 13, for detachably supporting the scale 16 by the sleeves 6 and 7 and the web 8. The scale 16 extends vertically from the extension 12 and passes through a cut out portion 18 which is formed in the base 1, so as to permit of the adjustments of the scale for measuring distances outwardly from the finished or machine face 3 of the base support 1 for measuring therefrom.

The standards 4 and 5 have slidably mounted thereon sleeves 20 and 21, which sleeves are connected by a web 22. The sleeve 21 is split and has tangentially extending ears 23 and 24 formed thereon, which are perforated, the ear 23 having an inter-

nally screw threaded perforation, while the ear 24 has a smooth perforation. The perforations formed in the ears 23 and 24 receive the shank 25 of a thumb screw 26, which is provided for clamping the sleeve 21 securely upon the standard 5 for holding the sleeves 20 and 21 and the web 22 in various adjusted positions along the length of the standards 4 and 5.

10 The web 22 is provided with a transversely extending opening 27 formed therein, in which opening is seated a thumb nut 28. The thumb nut 28 is mounted upon an externally screw threaded feed rod 29, which extends through a vertical opening formed in the web, and downwardly into and partially through an opening 30 which is formed centrally in and extends through the supporting base 1. The upper end of the feed rod or screw 29 is rigidly and securely connected to a lug 31, which is formed upon and depends from the web 8.

15 In the operation of the improved adjustable scale holder, when it is desired to adjust the scale 16 for comparatively large adjustments with respect to the base 3, the thumb screws 26 and 11 are loosened, and the respective sleeves and webs are moved upon the standards 4 and 5 until the proper 20 section of the scale projects beyond the base 3 of the supporting base 1. For minute adjustment of the scale, the thumb screw 26 is tightened which securely clamps the sleeves 20 and 21 upon the standard, and the set 25 screw 11 is loosened so as to permit of the sliding movement of the sleeves 6 and 7 and consequently of the scale 16 which is carried by the extension 12. After the set screw 11 has been loosened, the thumb nut 28 is manually rotated, which feeds the feed rod 29 therethrough, and through the opening 30, moving the sleeves 6 and 7 and consequently the scale in proportion with the distance of movement of the feed rod or screw 29, by 30 means of which minute and exact adjustments of the scale 16 may be obtained, as is sometimes necessary in the laying out of a piece of work by a machinist, pattern maker or the like. Further adjustment of the scale 16 is provided by loosening the thumb screw 35 15, which will relieve the frictional binding engagement of the thumb screw head against the edge of the scale, and permit of the longitudinal sliding movement of the scale within the recess 13, or of the removal 40 of the scale from the recess if it is so desired.

45 From the foregoing description taken in connection with the accompanying drawing 60 the advantages of construction and of the method of operation of the improved adjustable scale holder will be readily apparent to those skilled in the art to which this invention appertains and, while in the foregoing description, the principle of the op-

eration of this invention has been described together with various features of construction, it is to be understood that certain minor features of construction, combination and arrangement of parts may be altered to 70 suit practical conditions provided such alterations are comprehended within the scope of what is claimed.

What is claimed is:

1. In a scale holder, a supporting base, 75 a pair of vertical standards carried by and extending upwardly from said base, said supporting base being provided with a recess formed therein and extending inwardly from the periphery, a scale means carried by said standards for adjustably supporting said scale, said scale extending vertically from said supporting base and having its lower end extending into said recess.

15 2. In an adjustable scale holder, a supporting base having its lower surface machined, a pair of standards secured to and extending upwardly at right angles to the lower surface of said base, two pairs of sleeves slidably mounted upon said standards, a web connecting each pair of said sleeves, means for clamping said sleeves in 90 adjusted positions upon said standards, and an extension formed upon one of said sleeves and projecting transversely therefrom and 95 having means for detachably supporting a scale.

3. In an adjustable scale holder, a supporting base having its lower surface machined, a pair of standards secured to and 100 extending upwardly at right angles to the lower surface of said base, two pairs of sleeves slidably mounted upon said standards, a web connecting each pair of said sleeves, means for clamping said sleeves in 105 adjusted positions upon said standards, an extension formed upon one of said sleeves and projecting transversely therefrom and having means for detachably supporting a scale, and means carried by said vertical 110 standards and connected to said webs for adjusting said sleeves and said webs along the length of said standards.

4. In an adjustable scale holder, a supporting base having its lower surface machined, said supporting base being provided with an opening extending vertically through the central axis thereof, a pair of standards secured to said base and extending upwardly therefrom, two pairs of 120 sleeves slidably mounted upon said standards, a web connecting each pair of said sleeves, one of each pair of said sleeves being split and having tangentially extending ears formed integrally therewith, a thumb 125 screw carried by said ears for clamping said sleeve in adjusted positions upon one of said standards, an extension formed upon one of said sleeves and extending transversely therefrom, said extension being provided 130

with a facial recess, and a thumb screw carried by said extension for clamping a scale in said recess.

5. In an adjustable scale holder, a supporting base having its lower surface machined, said supporting base being provided with an opening extending vertically through the central axis thereof, a pair of standards secured to said base and extending upwardly therefrom, two pairs of sleeves slidably mounted upon said standards, a web connecting each pair of said sleeves, one of each pair of said sleeves being split and having tangentially extending ears formed integrally therewith, a thumb screw carried by said ears for clamping said sleeve in adjusted positions upon said standards, an extension formed upon one of said sleeves and extending transversely therefrom, said extension being provided with a

facial recess, a thumb screw carried by said extension for clamping a scale in said recess, the second pair of sleeves slidably carried by said standards and positioned beneath said first named sleeves, a web connecting said second named sleeves, means for clamping said second named sleeves in various adjusted positions upon said standards, and a feed screw extending through said second named web and connected to said first named web for moving said first sleeves and said scale longitudinally along said standards.

In testimony whereof I affix my signature in presence of two witnesses.

MICHEAL F. CUBIAC.
